UNITED STATES PATENT OFFICE.

MAX BECKER, OF NEW YORK, N. Y.

BED-LOUNGE.

SPECIFICATION forming part of Letters Patent No. 257,640, dated May 9, 1882.

Application filed March 15, 1882. (No model.)

To all whom it may concern:

Be it known that I, MAX BECKER, a citizen of the United States, residing at New York, in the county and State of New York, have invented new and useful Improvements in Bed-Lounges, of which the following is a specification.

This invention relates to that class of lounges convertible into a bed; and it consists in the construction and arrangement of parts herein-after described, tending to afford various facilities or conveniences of use.

This invention is illustrated in the accompanying drawings, in which Figure 1 is a longitudinal section through the seat-frame when it is unfolded to form a bed. Fig. 2 represents a side view, partly in section. Fig. 3 is a plan or top view when the seat-frame is unfolded. Fig. 4 is a cross-section. Fig. 5 is a detail view, showing the catch for retaining the head-board in a folded position upon the seat-frame.

Similar letters indicate corresponding parts.

The letter A designates the main frame of the lounge, and B a seat-frame, which is hinged to the main frame, as at C, to swing or fold upon it, as shown in Fig. 1, or to unfold to the position shown in Figs. 2, 3, and 4. The main frame A is raised at one end, forming an arm, A', and the seat-frame B carries an arm, B', which is adapted to fold upon said arm of the main frame. The seat B also carries the back D of the lounge, and when the seat-frame is unfolded this back rests upon the floor, thus forming, together with the hinge-joints C, a support for the seat-frame. An ornament, E', is removably attached to the back, and is taken off when the seat-frame is unfolded. The back D projects downward below the seat-frame, forming a longitudinal rail, D', and when the seat-frame is unfolded to form a bed this rail is brought to the outer edge of the bed and answers the purpose of a bedstead-rail. When the seat-frame is folded the longitudinal rail D' of the back is brought behind and below the main frame A, as shown by dotted lines in Fig. 4.

To the cross-piece B², at the upper end of the

seat-frame, is hinged a head-rest, G, the letter o indicating the joints employed for this purpose, and when this head-rest is unfolded to a position for use it is supported by the arm A' of the main frame, as shown in Figs. 3 and 4, said arm being provided with an inclined ledge or shoulder, I, to receive the head-rest. When not in use the head-rest G is folded on the seat-frame, and it is retained in that position by a spring-catch, H, Fig. 5, which is secured in a recess, J, on the inner surface of the projecting rail D' of the back, such catch yielding to the passage of the head-rest in folding or unfolding the same.

What I claim as new, and desire to secure by Letters Patent, is—

1. In a bed-lounge, the combination, with the stationary main frame A, of the seat-frame B, hinged to the front edge thereof, and provided with an attached back, D, having a longitudinal rail, D', projecting downward below the under side of the seat-frame substantially the entire length thereof, and normally resting behind the main frame, but constituting a vertical bedstead-rail when the hinged seat-frame is opened, substantially as described.

2. In a bed-lounge, the combination of the stationary main frame A, the hinged seat-frame B, provided with a cross-piece, B², and an attached back, D, having a longitudinal rail, D', projecting downward below the under side of the seat-frame, and normally resting behind the main frame, but constituting a vertical bedstead-rail when the hinged frame is opened, and the head-rest G, hinged at its lower edge to the cross-piece of the seat-frame, and when in an open position supported by the head-piece of the main frame, substantially as described.

In testimony whereof I have hereunto set my hand and seal in the presence of two subscribing witnesses.

MAX BECKER. [L. s.]
